UNITED STATES PATENT OFFICE.

LEWIS H. BRADSHAW, OF ALLEGHENY, PENNSYLVANIA.

LEVEL.

SPECIFICATION forming part of Letters Patent No. 781,995, dated February 7, 1905.

Application filed October 3, 1904. Serial No. 227,012.

To all whom it may concern:

Be it known that I, LEWIS H. BRADSHAW, a citizen of the United States of America, residing at Allegheny, in the county of Allegheny, and State of Pennsylvania, have invented certain new and useful Improvements in Levels, of which the following is a specification, reference being had therein to the accompanying drawings.

10 This invention relates to certain new and useful improvements in levels, and more particularly to the level-glasses thereof.

15 The object of this invention is to provide a novel form of level-glass which may be firmly secured in a level and protected from being injured.

Another object of this invention is to provide a level-glass which may be readily secured in the levels commonly used, and in 20 constructing my improved level I have embodied such features of construction as to reduce the cost of manufacture to a minimum, at the same time maintaining a strong and durable construction.

25 Briefly described, my improved level comprises a body portion which is provided with a plurality of openings, and in each of these openings is mounted a metallic casing which is adapted to contain the level-glass. The 30 casing is provided with cut-away portions or openings through which the glass will be visible and the level so constructed that in case the glass should become broken the casings may be removed and new glasses placed therein.

35 The above construction will be hereinafter more fully described and then specifically pointed out in the claims, and referring to the drawings accompanying this application like numerals of reference designate corresponding parts throughout the several views, in which—

40 Figure 1 is a side elevation of my improved level, a portion of the body of said level being broken away, and in one of the openings of said level I have illustrated the level-glass casing in vertical section, while in the other openings thereof I have illustrated the same in side elevation. Fig. 2 is a side elevation of a level-glass employed in connection with

the level. Fig. 3 is a vertical sectional view 50 of my improved level, and Fig. 4 is a detail perspective view of the level-glass casing in an opened position.

When constructing my improved level, I intend to use a suitable material, such as wood 55 or metal, for the body portion of the level, and the body portion is to be provided with a plurality of openings in which my improved level casing and glass is mounted. In the accompanying drawings I have illustrated three 60 openings in connection with my improved level, each opening being constructed identical with the other, and I do not care to confine myself to the exact number of openings that may be formed in the level, as one or 65 more of these openings may be dispensed with and a level provided having only one opening formed centrally therein.

The reference - numeral 1 designates the body portion of the level, and the reference- 70 numeral 2 the openings formed in the body portion. These openings are provided with beveled edges 3 3, and to these edges are secured the level-glass casings 4, containing the level-glasses. As each opening and each level- 75 glass casing is identical, I deem it only necessary to describe one of said openings containing a level-glass.

The level-glass casing, which is clearly illustrated in Figs. 3 and 4 of the drawings, is 80 formed of sheet metal or the like material and consists of the sides 5 5, the edges of which are bent inwardly, as indicated at 6, the corners of each side 5 being provided upon the exterior thereof with lugs 7, said lugs having 85 openings 8 formed therein, whereby screws 9 may be employed for securing the lugs upon the beveled edges 3 of the openings 2. The inner faces of the sides 5 are provided with a plurality of inwardly-extending lugs 10, which 90 are adapted to engage the inner sides of the level-glass 11. The level-glass is preferably constructed whereby it will conform to the contour of the casing 4, and the inwardly-extending edges 6 of said casing will support 95 the level-glass upon the exterior sides of the same, while the lugs 10 will support the inner sides of said level-glass and prevent the

same from moving within the casing when the level-glass has been placed therein. The edges of the casing are cut away, as indicated at 12 12, whereby openings will be formed in 5 the casing when the same has been placed around the level-glass, these openings permitting the level-glass to be exposed, whereby it may be observed when the level is to be used.

By employing the level-glass casing and by

- 10 securing the same within the opening 2 of the level it will be impossible for the level-glass contained within the same to become displaced or in any manner injured by the rough usage to which level-glasses are generally subjected.
- 15 If it be desired, openings may be formed in the edge of the level communicating with the openings formed in the side of the level, as shown in Fig. 3, whereby the level-glass may be observed from the top edge of the level.
- 20 It will be seen by the peculiar rectangular shape of the glasses and the casings that a space will exist between the edges of the casing and the sides of the openings formed in the level, and this space will permit of the 25 level-glass being observed from the sides of the level. By forming openings in the casing upon the four sides thereof the level-glass may be observed from four different positions that the level may assume—that is, the glass 30 may be observed when the level is standing on either one of its ends or lying upon either one of its edges.

It will be noted that various changes may be made in the details of construction without

departing from the general spirit and scope of 35 the invention.

What I claim, and desire to secure by Letters Patent, is—

1. A level comprising a body portion having an opening formed therein, a casing consisting 40 of half-sections, each provided with laterally-extending pierced lugs and a level-glass mounted in said casing.

2. A level comprising a body portion having a plurality of openings formed therein, a rectangular casing mounted in each opening, a rectangular level-glass mounted in each casing, each casing having openings formed 45 therein, means for supporting level-glasses within said casings, and means for supporting 50 said casings within said openings, substantially as described.

3. The combination with a level-body having an opening with beveled edges, of a casing seated in said opening, said casing being 55 formed of two similar sections each having laterally-extending pierced lugs resting on the beveled edges of the opening in the body and inwardly-extending lugs, and a level-glass mounted between the sections of the casing 60 and sustained in position by said inwardly-extending lugs.

In testimony whereof I affix my signature in the presence of two witnesses.

LEWIS H. BRADSHAW.
